JOHN BROWN, OF NIAGARA FALLS, NEW YORK.

CONVEYING DEVICE FOR SIFTING-MACHINES AND THE LIKE.

1,100,213.

Specification of Letters Patent. Patented June 16, 1914.

Application filed July 1, 1913. Serial No. 776,780.

To all whom it may concern:

Be it known that I, JOHN BROWN, a citizen of the United States, residing at Niagara Falls, in the county of Niagara and State of New York, have invented new and useful Improvements in Conveying Devices for Sifting-Machines and the like, of which the following is a specification.

This invention relates to a conveying device which is more particularly designed for use in a sifting machine in which the screens or sieves are mounted in a horizontally rotating or gyrating box or chamber and which requires means whereby this box or chamber is movably connected with the stationary bin, hopper or source of supply of the material to be sifted and also means whereby the separated material is discharged from the sifting box to a stationary receptacle.

Heretofore the connections between the sifting box and the stationary source of supply and the stationary receiving device were effected by means which comprised pliable or flexible tubes made of textile fabric, each tube being connected at one end with the movable sifting box while its other end was connected with the companion stationary member of either the supplying or receiving device. This form of chute or spout for conducting the material to and from the sifting box is objectionable for the reason that it wears out very rapidly and therefore requires frequent renewal in order to prevent the loose material which is being sifted, such as flour, from escaping into the building where it is not only lost but also is dangerous and injurious.

It is the object of this invention to provide improved means for connecting the movable sifting box with the stationary devices from which the sifting machine is supplied with the material to be sifted and which receive the material after being sifted, these means being so organized that they are very durable, inexpensive in construction and not liable to get out of order so that renewal of the same is only necessary at infrequent intervals and the machine therefore does not have to be stopped very often for this purpose.

In the accompanying drawings Figure 1 is a vertical section of a flour sifting machine provided with my improvements. Fig. 2 is a vertical section, on an enlarged scale, of one of the conveying devices

whereby the sifting box is connected with an adjacent stationary supplying or receiving device. Figs. 3 and 4 are horizontal sections in the correspondingly numbered lines in Fig. 2.

Similar characters of reference indicate corresponding parts throughout the several views.

Although my improvements are applicable to sifting machines which may vary in details of construction that shown in the drawings, as an example, comprises a horizontally rotating or gyrating box or chamber 1 arranged between the ceiling 2 and the floor 3 of the building and containing one or more sieves 4 whereby the flour or similar material which is delivered into the upper end thereof is separated or graded as to size and delivered at the lower end thereof.

Any suitable means may be provided for effecting the horizontal rotating or gyrating movement, and the sifting box may also be movably supported in any suitable manner, for instance, as shown in the drawings, by means of flexible upright suspension bars 5 secured at their upper ends to the ceiling while their lower ends are secured to the sifting box or chamber.

At its upper end the sifting box is connected with the stationary source of supply of material which is to be sifted by means of one or more of my conveying devices and at its lower end this sifting box or chamber is also connected by one or more conveying devices embodying my invention with a stationary receiver adapted to receive the separated material. Each of these conveying devices for delivering the material to be sifted either to the sifting box or discharging the separated material from the box is preferably constructed as shown in Fig. 2, it being assumed that the conveying device shown in this figure is one of those whereby the flour to be sifted is delivered from an overhead spout, bin or other stationary source of supply to the sifting box.

As shown in Figs. 2, 3 and 4, 6 represents a lower enlarged outer tube of sheet metal or other suitable material which communicates at its lower end with an opening in the top or upper end of the sifting box and is secured to the latter by means of nails or other suitable fastenings passing through an annular flange 7 on the lower end of the

tube and into the adjacent part of the sifting box. At its upper end the outer tube is provided with an annular rim or collar 8 which is preferably constructed of wood 5 and to the upper side of this wooden rim is secured a packing or facing 9 of leather or other suitable material.

10 represents an upper inner tube of smaller diameter than the outer tube and 10 also constructed preferably of sheet metal. This inner tube is arranged vertically and has its lower end projecting into the upper part of the outer tube while its upper end is secured to the lower end or bottom of the 15 bin, hopper or spout which supplies the material, such as flour, which is to be sifted. The bottom of this supply bin in this case is represented by the ceiling 2. The diameter of the lower tube is sufficiently large that the 20 same will constantly inclose the inner tube in all positions of the sifting box during the gyrating or rotating movement thereof, so that at all times a free communication is established between the interior of the inner 25 tube and the interior of the outer tube.

In order to close the space between the exterior of the inner tube and the upper end of the outer tube a cover, lid or shutter 11 having preferably the form of a disk or ring 30 and constructed of sheet metal is mounted on the outer side or periphery of the inner tube and adapted to engage slidingly with the upper edge of the outer tube and its rim. A dust tight joint is produced between this 35 cover and the outer tube by providing the underside of this disk with an annular packing or facing 12 of felt or similar material which rests upon the leather facing on the outer tube and rim. In order to permit the 40 cover to always lie firmly in engagement with the leather packing ring 9 this cover is mounted loosely on the inner tube so as to move freely axially relatively thereto, but a dust tight joint is produced between this inner 45 tube and the cover by means of a rim 13 of wood or other suitable material secured to the upper side of the cover around the inner tube, and a flexible collar 14 of flannel or other suitable material surrounding the inner 50 tube and secured at its upper end to the periphery of the inner tube while its lower end is secured to the wooden rim of the cover. By this means the cover is free to rise and fall the required extent on the inner 55 tube and remain firmly in sliding engagement with the upper edge of the outer tube, thereby providing a dust tight connection between the inner and outer tubes in all 60 positions of the sifting box relative to the source of supply.

The parts described so far may be utilized without the employment of anything else for conducting the flour or other material to be sifted from the inner tube into the outer tube and thence to the sieves of the box, and

the sifted material may in like manner be discharged from the sifting box to the receptacles intended to receive the same. When thus used the material flowing downwardly through the inner tube will be discharged 70 into the outer tube in all positions of these tubes relatively to each other in a horizontal direction. In order, however, to render the connection between the sifting box and the source of supply and the place of discharge 75 still tighter, an additional or auxiliary tube 15 is inserted vertically within the inner tube and provided at its upper end with an external annular flange 16 which rests upon the upper end of the inner tube while the lower 80 end of this auxiliary tube is connected below the lower end of the inner tube with the enlarged outer tube by means of a circular flexible diaphragm 17, as shown in Figs. 2 and 4. This diaphragm preferably is of accordian-shape and forms a flexible connection between the auxiliary tube and the outer tube which permits the outer tube to move freely horizontally relatively to the auxiliary tube during the rotating or gyrating 90 movement of the sifting box and still operates as a separating wall between the outer tube and the inner tube for more effectually preventing the passage of any dust to the exterior of the machine. This auxiliary tube 95 and diaphragm are, however, not usually necessary and may only be required when handling exceedingly fine material inasmuch as this conveying device without the use of the auxiliary inner tube and diaphragm 100 have been employed with perfect success in flour sifting machines of the type shown in the drawings.

When this conveying device is employed for delivering material from a source of supply to the sifting machine the inner tube, and the auxiliary tube if the latter is used, are the stationary tubular members and the outer tube is the movable tubular member, but when this device is employed at the 110 lower end of the sifting machine for discharging the separating material therefrom to a receiving place the outer enlarged tube becomes the stationary member and the inner tube, as well as the auxiliary tube if the 115 latter is employed, become the movable members of this conveying device.

This conveying device is exceedingly simple in construction, it has no delicate parts which are liable to get out of order, the same produces a perfectly tight joint between the stationary and movable parts of the machine, and the same can be renewed at comparatively low cost when worn out.

I claim as my invention:

1. A conveying device comprising a delivery tube having an outlet end, a receiving tube having an inlet end which communicates with the outlet end of the delivery tube, said tubes being capable of a relative 130

- gyratory movement in a plane at right angles to said tubes, and a cover mounted on the delivery tube and engaging with the inlet of the receiving tube.
- 5 2. A conveying device comprising a delivery tube having an outlet end, a receiving tube having an inlet end which communicates with the outlet end of the delivery tube, said tubes being capable of a relative gy- 55 ratory movement in a plane at right angles to said tubes and a cover mounted trans- versely and loosely on the delivery tube and engaging slidingly with the inlet end of the receiving tube.
- 10 3. A conveying device comprising a delivery tube having an outlet end, a receiving tube having an inlet end which communicates with the outlet end of the delivery tube, said tubes being relatively movable in a direction crosswise of the tubes and said receiving tube being of larger diameter than 60 said delivery tube and a cover mounted on the delivery tube so that its plane is at right angles to the length of said tube and engag- 65 ing with said receiving tube.
- 15 4. A conveying device comprising a delivery tube having an outlet end, a receiving tube having an inlet end which communicates with the outlet end of the delivery tube, said tubes being relatively movable in a direction crosswise of the tubes, a cover mounted loosely on the delivery tube so that its plane is at right angles to the length of said tube and engag- 70 ing with the inlet end of the receiving tube, an auxiliary tube arranged within the delivery tube, and a flexible connection between said auxiliary tube and said receiving tube. 75
- 20 5. A conveying device comprising a delivery tube having an outlet end, a receiving tube having an inlet end which communicates with the outlet end of the delivery tube, said tubes being relatively movable in a direction crosswise of the tubes, a cover mounted on the delivery tube and engaging with the inlet end of the receiving tube, an auxiliary tube arranged within the delivery tube and provided at its upper end with an 80 annular flange resting on the upper end of said receiving tube, and a flexible connection between said auxiliary tube and said receiving tube.
- 25 6. A conveying device comprising a delivery tube having an outlet end, a receiving tube having an inlet end which communicates with the outlet end of the delivery tube, said tubes being relatively movable in a direction crosswise of the tubes, a cover mounted loosely on the delivery tube so that its plane is at right angles to the length of said tube and engag- 85 ing with the inlet end of the receiving tube, and a packing interposed between the cover and the receiving tube.
- 30 7. A conveying device comprising a delivery tube having an outlet end, a receiving tube having an inlet end which communicates with the outlet end of the delivery tube, said tubes being relatively movable in a direction crosswise of the tubes, a cover mounted loosely on the delivery tube so that its plane is at right angles to the length of said tube and engag- 90 ing with the inlet end of the receiving tube, an auxiliary tube arranged within said delivery and receiving tubes, and an accordion- shaped diaphragm connecting said auxiliary 95 tube with said receiving tube below the outlet of said delivery tube.
- 35 Witness my hand this 28th day of June, 1913.

JOHN BROWN.
